COMBINED STRAIGHTEDGE AND
TRIMMERAlbert E. Ream, Braymer, Mo., assignor of one-
half to Ralph E. Goddard, Braymer, Mo.

Application March 15, 1941, Serial No. 383,565

7 Claims. (Cl. 164—77)

My invention relates to improvements in combined straight edges and trimmers, adaptable for the trimming of wall paper, cloth and other sheet material.

One of the objects of my invention is the provision of novel trimming means combined with a novel straight edge, in which the trimming means is below the upper surface of the straight edge.

A further object of my invention is the provision of a combined straight edge and trimmer, which is simple, cheap to make, durable, not likely to get out of order, which is easy to operate, and which is efficient in its operation.

Still another object of my invention is the provision of a novel trimming mechanism including two cutters having cutting edges disposed in longitudinal alinement, arranged to simultaneously reciprocate in like directions and projecting the same distance below the straight edge side, to assure complete severance of the material that is being trimmed.

The novel features of my invention are fully hereinafter set forth and claimed.

In the accompanying drawing illustrating the preferred embodiment of my invention,

Fig. 1 is a plan view of my combined straight edge and trimmer operatively disposed on and trimming a sheet of material disposed upon a suitable flat support.

Fig. 2 is an enlarged perspective view, partly broken away of my straight edge and trimmer.

Fig. 3 is an enlarged cross section through the implement in the plane of the axis of the handle, supporting one of the cutters.

Fig. 4 is an enlarged perspective view of the reciprocative member.

Fig. 5 is an enlarged cross section through a portion of the implement in the plane of the axis of the screw, supporting the other cutter.

Similar characters of reference designate similar parts in the different views.

The straight edge comprises a rectangular member 1, one longitudinal edge of which is straight and has in it a longitudinal groove 2, and a longitudinal flat rectangular plate 3 fastened to the grooved edge of the member 1, and having its outer side straight and forming the straight side edge of the straight edge. The plate 3 has through it a longitudinal slot 4 which registers with the groove 2 and forms therewith a longitudinal channel in which is reciprocative a member as a bar 5, substantially rectangular in cross section, and having a longitudinal side rib 6 reciprocative in the slot 4.

Horizontally extending transversely through

the rib 6 and reciprocative member 5 are two threaded holes 7 and 8.

A handle 9 having the form of a knob is fixed to the member 5 by a threaded stem 10, fitted in the hole 7. The handle 9 has an annular shoulder 11 bearing against the rib 6. A screw 12 has its threaded stem 12 fitted in the hole 8. It has an annular shoulder 13 bearing against the rib 6.

Two cutters 14 and 15 are respectively rotatably mounted on the shoulders 11 and 13. Each cutter has a circular peripheral beveled cutting edge. Said cutting edges are respectively designated 16 and 17. The cutting edges 16 and 17 are longitudinally alined, are next to the plate 3 and project at all times the same distance below the lower edge of the plate 3, and are adapted to trim when moved in either direction.

In operation, the sheet 18, of wall paper, cloth, or other material to be trimmed, is placed on a suitable flat top support 19, and the straight edge, 1—3, is then suitably adjusted on the sheet 18, as shown in Fig. 1, with the cutting edges 16 and 17 bearing on the sheet 18. The handle 9 is then used to slide the member 5 to the right, as viewed in Fig. 1, upon which the cutting edges 16 and 17 will sever from the sheet the trimmed strip 20.

Two alined cutters 14 and 15 are employed to insure the complete severance of the sheet that is being trimmed. With the use of a single cutter, the severed strip sometimes adheres to the sheet at different points and requires hand separation at such points.

The upper surface of the support 19 for the sheet, is, preferably, of some soft metal, such as sheet zinc on which the cutting edges 16 and 17 travel.

It will be noted that no portion of the cutting edges 16 and 17 project above the upper surface of the straight edge, so are not liable to have contact with the hands of the operator.

The reciprocative member 5 and the plate 3 are preferably of metal, the member 5 being freely reciprocative in the groove 2, and the rib 6 being snugly slidably fitted in the slot 4.

While in Fig. 1 the cutters are shown as being started from the left, they may be started from the opposite longitudinal edge of the sheet 18. The slot 4 is longer than the width of any sheet to be trimmed. If the strip 20 is longer than the slot 4, the implement will be adjusted longitudinally on the sheet, or the sheet will be adjusted to suit this condition.

One end of the slot 4 is open so that the member 5 can be slid out for cleaning and sharpening purposes.

It will be noted that all portions of the straight edge and trimmer, excepting the lower edges of the cutters 14 and 15, are disposed wholly between the planes of the upper and lower flat sides of the bar 1. There are no parts projecting above said bar, and only a slight projection of the cutters 14 and 15 below the bar 1, whereby the device occupies a minimum of space, and can be disposed in compact form for storage or shipment, and the absence of upwardly protruding parts avoids interference with the easy manipulation of the device in use. By having the rotary cutter edge 16 always disposed below the bottom of the straight edge member 1, and said member disposed on top of the sheet to be cut, there is nothing to interfere with trimming any desired width from the sheet.

Modifications of my invention, within the scope of the appended claims, may be made without departing from the spirit of my invention.

What I claim is:

1. In a combined straight edge and trimmer, a straight edge member which rests on the sheet to be trimmed as it is trimmed and having in its straight edge side a longitudinal channel, a bar longitudinally reciprocative lengthwise in said channel, a handle fixed on and adapted to reciprocate said bar, and a rotary circular cutter having a peripheral beveled cutting edge and rotatably mounted on said handle with said cutting edge next to and projecting at all times below said member and its straight edge side and adapted to trim when moved in either longitudinal direction.

2. In a combined straight edge and trimmer, a straight edge having in its straight edge side a longitudinal channel, a member longitudinally reciprocative in said channel and having a horizontal transverse threaded hole, a rotary cutter having a circular peripheral beveled cutting edge, and a handle having a threaded stem fitted in said threaded hole and rotatably supporting said cutter with said cutting edge next to and projecting below said straight edge side.

3. In a combined straight edge and trimmer, a straight edge having in its straight edge side a longitudinal channel, a member longitudinally reciprocative in said channel, a handle fastened to said member for reciprocating said member, two rotary cutters each having a circular peripheral beveled cutting edge, and means rotatably supporting said cutters on said member with their cutting edges spaced apart in longitudinal alignment and next to and extending below said straight edge side.

4. In a combined straight edge and trimmer, a straight edge having in one longitudinal side

edge a longitudinal groove, and having fastened to said side edge a longitudinal plate having a longitudinal slot in register with said groove and forming therewith a longitudinal channel, a member reciprocative in said channel longitudinally, and having a transverse horizontal threaded hole registering with said slot, a handle having a threaded stem fitted in said hole, two rotary cutters each having a circular peripheral beveled cutting edge, and means rotatably supporting said cutters on said member with their cutting edges next to and projecting below said plate, which plate serves as the straight edge side of said straight edge.

5. A combined straight edge and trimmer comprising a rectangular member having a straight side edge provided with a longitudinal channel, a bar reciprocative lengthwise in said channel, a handle fixed on and adapted to reciprocate said bar, and a rotary cutter rotatable on said handle flatwise against said side edge and having a peripheral cutting edge below the upper side of said member and extending at all times below the lower side of said member and adapted to trim when moved longitudinally in either direction, all portions of said straight edge and trimmer, excepting the lower portion of said cutter, being disposed wholly between the planes of the upper and lower sides of said member.

6. In a combined straight edge and trimmer, a bar adapted to rest on the material that is being trimmed and having a longitudinal straight edge provided with a longitudinal channel, a member longitudinally reciprocative in said channel, a handle fastened to said member, a rotary cutter having a circular peripheral cutting edge next to said straight edge, and means on said member rotatably supporting said cutter with said cutting edge at all times lower than the upper side and projecting lower than the under side of said bar.

7. In a combined straight edge and trimmer, a bar having flat upper and under sides and a straight edge with a longitudinal channel between said sides, said bar being adapted to rest on the material that is being trimmed, a member longitudinally reciprocative in said channel, a handle fastened to said member, a rotary cutter having a circular peripheral cutting edge next to said straight edge, and means on said member rotatably supporting said cutter with said cutting edge at all times lower than the upper side and projecting lower than the under side of said bar, all of the parts of the trimmer being disposed lower than the upper side of said bar.

ALBERT E. REAM.
